UNITED STATES PATENT OFFICE.

ANTON KOPECKY, OF CHICAGO, ILLINOIS.

MITER BOX.

Application filed January 3, 1927. Serial No. 158,512.

This invention relates to improvements in miter boxes, and has among its principal objects to provide a miter box which shall be so constructed and arranged as to afford a comparatively high degree of accuracy in the cutting of moldings and the like, and which shall be adjustable for cutting the ends of such moldings and the like at various predetermined angles.

10 Another object of the invention is to provide a miter box having a pair of stages for supporting a pair of moldings and the like, whereby the ends of two of said moldings may be simultaneously cut at the desired angle without the necessity of cutting the end of one of such moldings and then resetting the mechanism of the miter box to cut the oppositely disposed angle of the end of the other molding, as is commonly provided in existing miter boxes.

A further object of the invention is to provide a miter box having a mechanism for simultaneously imparting movement to the stages thereof for oscillatably moving such stages in relatively opposite directions and with the same degree of angular movement.

A still further object of the invention is to provide such mechanism whereby one of said stages may be moved independently of the other to selectively vary their distance apart from each other without disturbing their relative angular position, whereby two moldings and the like of various widths may be inserted into the miter box for simultaneously cutting the co-operating ends of such moldings at the desired angle, that is, one of such stages may be adjusted by independent movement parallelly with the longitudinal center line which passes through the pivotal centers of the stage, or in other words, one of said stages is independently movable or adjustable parallelly with the longitudinal center line of the saw.

45 Another object of the invention is to provide adjustable means for securely retaining the moldings and the like onto their supporting stages.

With the above and other objects in view, my invention consists in the novel combination, construction and arrangement of the parts and members shown in a preferred embodiment in the accompanying drawings, described in the following specifications, and particularly pointed out in the appended claims.

Referring to the drawings, Figure 1 is a plan view of a miter box embodying the preferred construction of my invention;

Figure 2 illustrates a longitudinal section 60 taken on line 2—2 of Figure 1.

Figure 3 is a cross section taken on line 3—3 of Figure 2;

Figure 4 is also a cross section taken on line 4—4 of Figure 2; 65

Figure 5 is a sectional plan view taken on line 5—5 of Figure 2, showing the mechanism for operating stages;

Figure 6 is a cross section taken on line 6—6 of Figure 2, showing substantially an 70 end elevation of the miter box and the stages therefor;

Figure 7 is a cross section taken on line 7—7 of Figure 5;

Figure 8 is a cross section taken on line 75 8—8 of Figure 2;

Figure 9 is an enlarged detail in cross section taken on line 9—9 of Figure 6; and,

Figure 10 is a cross section taken on line 10—10 of Figure 9. 80

Referring now to the illustrations, 15 indicates the base plate upon which is mounted a pair of bearing blocks 16 and 17 for slidably supporting the saw-carrying base member 18. The base member 18 is formed with 85 beveled sides whereby vertical or crosswise displacement is overcome but longitudinal movement thereof readily afforded. The saw 19 and supports 20 may be of any suitable design or construction and it will here 90 suffice to state that the supports 20 comprise retaining members 20^A which permit a longitudinal movement of the saw therein and which are slidably supported on the vertically disposed rods 20^B. The rods 20^B 95 are rigidly mounted on the base member 18.

The base member 18 is provided with a pair of spaced plates 18^A as a lower guide for the saw teeth, and which plates are mounted on a level with the two stages 21 100 which support the molding or the like during the cutting operation.

The stages 21 are provided with pivot arms 21^A formed preferably integrally with the lower faces thereof and having comparatively thinner extensions 21^B for pivotal support. As viewed in Figures 1 and 5, the left hand stage arm 21^A is pivotally supported on the bearing 22 and the right hand stage is pivotally supported on the traveling nut 23 which is screw-mounted on the threaded shaft 24. 105 110

The stages 21 comprise flat base plates 21^c and a longitudinally extending partition 21^d. The base 21^c of the right-hand stage 21 is additionally supported on a pedestal 25 fixed to the base thereof and slidably supported on the base 15.

The outer edge of the left-hand stage base 21^c is supported on the quadrant 26 and guided by means of integrally cast guides 21^e which engage the underside of the quadrant 26. A suitable indicator arrow 21^f is fixed to the outer edge of the left-hand stage 21 which is adapted to register with the indications 26^a on the face of the quadrant to show the angular position of the stages 21 and their partition walls 21^d. The quadrant 26 is rigidly supported on the posts 26^b upon the base 15.

To afford the simultaneous setting of the two stages 21 at like angles, I provide the following mechanism:

A longitudinally disposed screw 27 mounted in bearing 28 is provided which is threaded as at 27^a and equipped with a hand-wheel 27^b. An arm 29 having a pair of integral extensions 29^a threaded on the screw portion 27^a is positioned for movement in the guide 30. The other end 29^b of the arm 29 is threaded to receive the threaded portion of the tube 31 and a link 32 is pivotally mounted upon the extension 29^b at one end and at the other end has pivotal connection with the arm 21^a of the left-hand stage 21.

A sliding block 33 is rigidly fixed to the end of the tube 31 which tube 31 is mounted for reciprocation within the guide 34 which is fixed to the base 15. It will be observed that the end 29^b of the arm 29 is also provided for slidable movement within said guide 34. A link 35 is pivotally mounted to the block 33 at one end, the other end of which is also pivotally connected to the arm 21^a of the right-hand stage 21.

Referring now to the traveling nut 23, it will be observed that same is mounted for slidable movement or reciprocation within the guide 36 which is also securely mounted to the base plate 15.

Referring now particularly to Figures 2, 3, 4 and 5, the shaft 24 is provided at its outer end with a suitable hand wheel 24^a and at its inner end with an integral extension 24^b of substantially rectangular cross section, the narrower faces of which are curved to conform to the curvature of the inside of the tube 31. The tube 31 is designed to slide over the extension 24^b, however, by means of the provision of two short plates 37 inserted within the inner end of the tube 31, and rotation of the shaft 24 will impart rotation to the tube 31.

The rotation of the hand wheel 27^b will impart rotary movement to the threaded portion 27^a of the shaft 27, and will cause a sliding movement of the arm 29^b, whereby

the tubular member 31 may be caused to move inwardly over the extension 24^b toward the threaded portion of the shaft 24, thus causing a simultaneous inward movement of the two links 32 and 35 to thereby cause an oscillating movement of the arms 21^a of the two stages. It will now be clear, that both stages 21 will be moved through the same degree of movement and that the amount of such angular movement of the two stages may be clearly ascertained by reference to the indicator 21^f and its relative position to the indications on the quadrant 26. Should a wide molding or the like necessitate the lateral movement of the right hand stage without disturbing the relative angular positions of the two stages, a sliding movement of the right hand stage 21 may be accomplished by the rotation of the hand wheel 24^a which will cause a rearward movement of the traveling nut 23 on the threaded portion of the shaft 24 simultaneous with the rotation of the threaded tubular member 31 through the threaded end 29^b of the arm 29, and as the block 33 is rigidly fixed relatively to such tubular member 31, the block 33 will necessarily also move rearwardly to move the right hand stage rearwardly without disturbing the angular relation of the link 35 and the arm 21^a of the right hand stage.

In the illustrations the numerals 38 indicate moldings or the like positioned in place on the stages against the partition walls 21^d and securely held in place on the stages by means of U-shaped retainers 40. It will be observed that the retainers 40 are provided with a pair of longitudinal slots 40^a within the horizontal leg thereof, to afford longitudinal adjustment on the stages, and that suitable bolts 41 with wing nuts are provided for fastening the retainers to the stage. The bolts 41 are adjustably mounted in the slots 21^s within the stages which slots are disposed right angularly to the slots 40^a within the retaining members to afford cross-wise adjustment of the retaining members for moldings of varying widths.

To provide additional retaining members for comparatively high moldings, clamping members generally indicated by numeral 42 are provided on the partition walls 21^d. Each of the clamps 42 comprises a threaded bolt 42^b, upon which is mounted the block 42^a. Within the block 42^a and upon the bolt 42^b is a securing nut of circular shape 42^c. The bolts 42^b are secured to the wall 21^d by means of a screw 42^d. The block 42^a is provided with a passage 42^e extending at right angles to the bolt 42^b and adapted to carry the shank 42^f, to the other end of which is rigidly mounted a bearing plate 42^g. It will now be readily apparent that the bearing plate 42^g with its shank 42^f is slidably mounted in the passage 42^e to afford

adjustment of the bearing plate 42^c to the desired point on the face of the moldings which may be held against the wall 21^b, and also that since the block 42^a is loosely 5 or pivotally supported on the bolt 42^b, such block may be disposed or adjusted in any desirable position to present the bearing plate 42^a and its shank 42^c at any desirable angle. When the clamp 42 is adjusted, the 10 same can readily be firmly tightened by the operation of the nut 42^c.

From the above description and attached illustrations, it is believed that an extended description of the operation will not be 15 necessary, as the same will be readily apparent to those skilled in the art. However, it may be stated that the saw-supporting device and its base 18 may be readily adjusted longitudinally relatively to the base 15 by 20 virtue of the slideable mounting of the base 18 within the bearings 16 and 17.

I claim:

1. In a miter box, and in combination, 25 a saw, a saw-supporting device, a pair of stages for supporting the work during the operation of said saw, mechanism for simultaneously moving said stages in relatively opposite directions and in like angular relation to said saw, and additional means for 30 moving one of said stages independently of the other of said stages to selectively vary their distance apart from each other without disturbing their relative angular positions.

2. In a miter box, and in combination, a 35 saw, a saw-carrying device, a pair of pivotally mounted stages for supporting the work during the operation of said saw, means for imparting movement to said stages for simultaneously oscillatably moving said stages in relatively opposite directions, and separate means for independently 40 moving one of said stages parallelly with

the center line passing through the pivotal centers of said stages.

3. In a miter box, and in combination, a 45 saw, a saw-carrying device, a pair of pivotally mounted stages for supporting the work during the operation of said saw, mechanism for imparting movement to said stages for simultaneously oscillatably moving 50 said stages in relatively opposite directions, and additional mechanism for moving one of said stages parallelly with the longitudinal center line of the saw and independently of the other of said stages to selectively 55 vary their distance apart from each other without disturbing their relative angular positions.

4. A miter box as embodied in claim 2, and including pivots for said stages, said 60 pivots being located in different points of a common plane.

5. A miter box as embodied in claim 3, and including pivots for said stages, said 65 pivots being located in different points of a common plane.

6. In a miter box, and in combination, a 70 saw, a saw-carrying device, a pair of pivotally mounted stages for supporting the work during the operation of said saw, mechanism for imparting movement to said 75 stages for simultaneously oscillatably moving said stages in relatively opposite directions, additional mechanism for moving one of said stages parallelly with the longitudinal center line passing through the pivotal centers of said stages independently of the other of said stages to selectively vary their distance apart from each other without disturbing their relative angular positions, and 80 means for indicating the relative angular positions of said stages.

In witness whereof I affix my signature.

ANTON KOPECKY.
